UNITED STATES PATENT OFFICE.

OSCAR E. NICKEY, OF BIG SPRINGS, TEXAS.

WATER-FILTER.

SPECIFICATION forming part of Letters Patent No. 644,537, dated February 27, 1900.

Application filed May 18, 1899. Serial No. 717,341. (No model.)

To all whom it may concern:

Be it known that I, OSCAR E. NICKEY, a citizen of the United States, residing at Big Springs, in the county of Howard and State 5 of Texas, have invented a new and useful Water-Filter, of which the following is a specification.

My invention relates to water-filters, and has for its object to provide a simple, compact, and efficient construction and arrangement of parts consisting in an improvement 10 upon a filter described and shown in Letters Patent No. 617,177, granted to me on January 3, 1899.

15 A particular object of the present invention is to provide means for the cleaning of the interior of the filter and the loosening of the coke or other filtering material to adapt it for further efficient use.

20 Furthermore, it is an object of my invention to provide improved means for attaching the filter to a faucet.

25 Further objects and advantages of this invention will appear in the following description, and the novel features thereof will be particularly pointed out in the appended claims.

30 In the drawings, Figure 1 is a perspective view of a filter constructed in accordance with my invention. Fig. 2 is a sectional view of the same, the reversing-valve casing being shown in elevation. Fig. 3 is a sectional view of the reversing-valve on the plane indicated by the line 3 3 of Fig. 2.

35 Similar reference characters indicate corresponding parts in all the figures of the drawings.

1 designates the cylindrical body of the casing, in which is arranged the filtering material 2, such as granulated coke, supported 40 between perforated upper and lower diaphragms 3 and 4. The upper diaphragm, as in the construction illustrated in my said former patent, is held in place by a spider or follower 5, actuated by a pressure-screw 6, the shank of said screw being arranged to extend through a stuffing-box 7, formed in the casing-cap 8, and the follower being provided with a central projection 9, extending upward 45 into a depending thimble 10 in the path of the lower end of the pressure-screw. Said

casing-cap 8 is secured in place by means of threaded studs 11, projecting upward from a flared flange at the upper edge of the casing through openings in the cap and engaged by 55 thumb-nuts 12, and as the outlet-faucet 13 of the filter is carried by said cap at an eccentric point it will be understood that by engaging different openings of the cap with the threaded studs 11 said outlet-faucet may be 60 arranged in either of a plurality of positions with relation to the body of the filter to suit the convenience of the operator. A gasket 14 is seated in registering grooves in the facing-surfaces of the cap and casing-cylinder. 65

Communicating with the casing through a lateral flush-port 15, located above the plane of the filtering material 2, is a reversing-valve casing 16, inclosing a double-faced or reversing valve 17, arranged to operate between 70 spaced seats 18 and 19, and communicating with the valve-casing between the planes of said seats is a coupling-arm 20, terminally constructed with a coupling or union 21 for engagement with a faucet 22, said coupling-arm 75 having a rocking or swivel connection with the valve-casing 16 to adapt the casing to be moved independently of the coupling-arm to suit the inclination of the discharge end of the faucet 22 and the preference of the operator. In the construction illustrated the coupling-arm is threaded in an opening in the side wall of the valve-casing 16, and also threaded upon said coupling-arm is a jam-nut 23, adapted to be adjusted toward the valve- 80 casing to lock the parts at the desired adjustment. Preferably a rubber gasket 24 is interposed between the adjacent faces of the jam-nut and valve-casing.

The flush-port 15, which communicates with 90 the filter-casing above the plane of the filtering material or medium, also communicates with the reversing-valve casing above the plane of the upper valve-seat 18, while communicating with the valve-casing below the 95 plane of the lower valve-seat and controlled by the reversing-valve when arranged upon said lower seat is a feed-pipe 25, which extends to and communicates with a feed-port 26, which opens into the filter-casing below 100 the plane of the filtering medium. In the construction illustrated a swivel coupling or

union 27 is employed to form the connection between the feed-pipe and a threaded nipple 28, which communicates with said feed-port.

At the lower end of the filter-casing is a sediment receptacle or pocket 29, preferably connected with the interior of the casing by a narrow port 30, formed in the neck portion of the casing, and communicating with this sediment-pocket is a drain-valve mechanism consisting of a valve 31, having a tubular stem 32, with the bore of which communicate ports 33, normally arranged within the guide of the valve-stem, but adapted to be arranged in communication with the interior of the casing when the valve 31 is unseated. The stem 32 extends through a stuffing-box having a gland 34 to prevent leakage when the drain-valve is unseated, and said stem below the stuffing-box is provided with a grip or hand-wheel 35. It will be noted that the drain-valve is constructed to seat downwardly and to rest directly upon a seat-surface which is in a plane perpendicular to the direction of movement of liquid or other material in leaving the casing through the port controlled by said valve, whereby the pressure of the contents of the casing serves to assist in maintaining the valve operatively seated. The same construction of valve is used in the reversing-valve mechanism, wherein the member 17 operates between parallel-faced valve-seats 18 and 19.

The filter-outlet-valve mechanism includes a casing 36, with which communicates the filter-faucet 37, and the valve 38, which is arranged to close against and seat in a direction perpendicular to the path of movement of water entering the casing 36. The valve consists of a disk 39 of metal or similar material and a packing-disk 40, the metallic holding-disk being secured in place by means of a screw 41 or the equivalent thereof, and it will be understood that the other valves included in the filter mechanism are similarly constructed.

I have found in practice that after water has been passing through a filter in one direction for a time the filtering material particularly adjacent to the plane of that diaphragm through which the water first passes becomes caked or adhesively connected by glutinous substances and that when the direction of the flow of water is reversed, while it removes the loose accumulations of foreign material, it fails to break up the cake of granulated coke or other material. Therefore in the filter embodying my present invention I construct the lower diaphragm to yield in a direction opposite to that in which the water ordinarily moves in passing therethrough, whereby when the direction of flow of water is reversed this diaphragm is moved or displaced and to a certain extent vibrated to cause the efficient shifting of the particles of coke within the space between the diaphragms, and particularly adjacent to the lower diaphragm, whereby the cake is broken up and

the parts of the mechanism returned practically to their original condition. In the construction illustrated the lower diaphragm is 70 yieldingly held in its normal or operative position by means of springs 42, consisting of coils from which extend arms 43 and 44, the former bearing against the under side of the diaphragm and the latter against fixed objects within the casing. I preferably construct each spring of a single blank of wire doubled upon itself at its center to form a loop, of which the closed end forms the upper arm 43 and of which the extremities are 75 turned downward to form studs 45, which fit in sockets in lugs 46, cast upon or secured to the inner surface of the casing below the plane of the lower diaphragm. Hence in practice the water which is supplied by the faucet enters the reversing-valve casing and passes from thence, when said valve is in its normal position, through the feed-pipe 25 to the interior of the filter-casing below the filtering medium. Particles of solid material which 80 may be in the water are allowed to settle in the sediment chamber or receptacle 29, while the passage of the water through the intermediate portion of the casing between the planes of the sediment-chamber and the filtering medium does not serve to disturb the contents of said chamber. After passing upward through the filtering material the water may be withdrawn through the filter outlet-valve, as required. After the apparatus has been 85 operated for a length of time sufficient to cause an accumulation of dirt the drain-valve should be opened and the reversing-valve reversed to cause water from the faucet 22 to enter the filter-casing through the flush-port 105 15, whereby it passes downward through the filtering medium and carries with it said accumulations. This downward movement of the water through the medium, however, serves to depress the lower diaphragm 4 and thus agitate and vary the positions of the particles of granulated coke, whereupon the filtering medium operates sufficiently when the several parts are returned to their normal positions.

In practice various changes in the form, proportion, size, and minor details of construction within the scope of the appended claims may be resorted to without departing from the spirit or sacrificing any of the advantages of the invention.

Having described my invention, what I claim is—

1. In a filter, the combination of a casing having spaced feed and flushing ports 26 and 15 respectively, spaced diaphragms and interposed filtering material arranged between the planes of said ports, means for holding upper diaphragm which is adjacent to the flushing-port against movement in a direction toward said port, springs for supporting the lower diaphragm above the plane of the feed-port and bearing against the same in a direction toward the first-named diaphragm so as

to yield in a direction opposite to that in which the water ordinarily moves in passing through the filter, and means for admitting liquid to the casing through either of said ports, substantially as specified.

2. In a filter, the combination of a casing having spaced feed and flushing ports, spaced diaphragms and interposed filtering material arranged between the planes of said ports, means for holding that diaphragm which is adjacent to the flushing-port against movement in a direction toward said port, said means consisting of a depressing - screw threaded in the casing, and a spider carried by said diaphragm and having said screw arranged in the path thereof, springs for supporting the other diaphragm and bearing against the same in a direction toward the first-named diaphragm, and means for admitting liquid to the casing through either of said ports, substantially as specified.

3. In a filter, the combination of a filter-casing containing a filtering medium and provided with feed and flushing ports and an outlet-valve, a reversing-valve having its casing in communication with said feed and flushing ports, a coupling - arm communicating with the valve-casing at its points of communication with said ports, and having a swivel connection with the casing, said coupling-arm being constructed for engagement with a supply-faucet, and a locking device for securing the reversing-valve casing in its adjusted position with relation to the coupling-arm, substantially as specified.

4. In a filter, the combination of a filter-casing containing a filtering medium and provided with feed and flushing ports and an outlet-valve, a reversing-valve having its casing in communication with said feed and flushing ports, a coupling-arm communicating with the valve-casing at its points of communication with said ports, and having a swivel connection with the casing, said coupling-arm being constructed for engagement with a supply-faucet, and a jam-nut threaded

upon the coupling-arm for securing the reversing-valve casing in its adjusted position with relation thereto, substantially as specified.

50

5. The filter-casing provided with a sediment receptacle or pocket, the drain-valve 31 having a tubular stem, and constructed to seat downwardly at the bottom of the receptacle or pocket, and a hand-operated device 55 for forcing the valve downward against its seat, substantially as described.

6. The filter-casing provided with a sediment receptacle or pocket, the stuffing-box fitted to the outlet thereof, the tubular valve- 60 stem carrying a valve which seats downwardly at the bottom of the receptacle or pocket, and a hand-wheel for the stem on the outside thereof, whereby the valve may be raised against the pressure of the contents of 65 the filter-casing, and is kept seated by the said pressure, substantially as described.

7. In a filter, the combination of a casing-cylinder containing a filtering medium and provided with lateral feed and flushing ports 70 and a bottom drain-port, a drain-valve controlling said drain-port, a reversing - valve for controlling said feed and flushing ports and provided with means for attachment to a supply-faucet, a casing-cap having a central pressure-screw for operating upon the filtering medium, and also provided with an annular series of spaced openings, threaded studs carried by the casing-cylinder to fit in said openings, and engaged by thumb-nuts, 80 said openings of the cap being adapted for engagement with different studs, and a filter outlet-faucet carried by the cap at an eccentric point and provided with a controlling-valve, substantially as specified.

85

In testimony that I claim the foregoing as my own I have hereto affixed my signature in the presence of two witnesses.
